Isaac Thompson,
Sects. Patents

The sole subscriber to in this Special Patent and marking party,
the same containing a description in the words of the said Isaac
Thompson himself of his Improvement in the Temple for the relief
and cure of Osteoia.

To all persons to whom these presents shall come. Isaac Thompson
son of Brattel Clark in the County of Windham and State of Vermont
sends greeting. Be it known that at Isaac Thompson have
invented construction aid and apparatus to use a new and use-
ful improvement in the construction of temples called Thompson's
Patent Temple specified in the words following, viz:

My Temple differs from those in common use in two particulars.
First the ball or pad instead of covering the entire aperture like
a lid is shaped as partially to enter it. To get this object in most
instances by making it of a shape partaking in part of the nature
of a cone and in part of a hemisphere, perhaps half way between
them; still as each individual patient requires a careful adap-
tation of this pad to his particular case I vary this shape a lot
so, sometimes a better fit is secured by making the pad or ball
like the upper or stem end of a pear, that is a cone rounded at the
apex and made flaring or trumpet shaped at the base.

In some instances I make them hemispherical but always endeavor
to adapt this shape to the size or aperture, have them per-
ticularly cut to it and have them so fitted to it that the patient wears
them with comfort. I usually turn these balls or cones of wood
and cover them with deer skin or shamrock leather, but have
again I find that some have so much tenderness and irritability
of the part that sponge, deer skin or some other substance softer
than wood is preferable. The other peculiarity of my temp consists
in all apparatus for adjusting it to the aperture and keeping

At this, Suppose a common steel trap hoop to terminate for crocodiles at the end to be worn in front in a round wire about as large as a goose quill. On this wire, like a watchman's cattle, turns a piece of trap to which the cone or pad is firmly attached at its base by a screw so that the patient can give the pad any degree of pressure into the aperture consistent with his comfort, and once adjusted to suit him it will stay there till he chooses to alter it. Construct this apparatus in the following manner. Make a trap hollow cylinder about half an inch in length and externally of about twice the diameter of the above mentioned wire. The inner or hollow diameter is filled to receive the wire. On its external cylindrical surface notches, teeth, or cog are filed slanting one way but the other side of each cog perpendicular or in the direction of the radius of the cylinder so that a tongue or spring of trap will slide easily over these teeth one way but will stand stiff like a brace if you attempt to move it in the opposite direction. This trap cylinder is slid on to the steel wire till it occupies about the middle of the hoop and then firmly soldered to the wire. I next take a piece of that trap of about that thickness called in merchandise $17^{\circ} 19$ light. It is about one twentieth of an inch in thickness. It should be from four to five inches in length (if the trap be intended for an adult) and in width about one inch and a quarter except at one end which should widen into a wide corresponding tongue with the base of the cone to which it is to be applied. I next saw longitudinally in the other or square end of this piece of trap two slots about an inch and a half long having between them in the middle a tongue about half an inch wide. I next cut off this tongue to about four thirds of an inch in length and file its ends to a bevel to fit the teeth or cogs in the above mentioned cylinder. I now apply the tongue to one of the notches in the cylinder, bend the two legs of trap around the wire to form a hinge and twist them in that position so that the tongue of trap forms a strong and brace and like that of a watchman's cattle always

lows a free motion in one direction but not in the other. When double bands are made on the above mentioned principle as also single ones for extremely lame or convalescent patients it is well to have the horse with its stirps propped round the body above the hip bones then band down these or about them inches and then in the shape of a wire band across the belly affording a comfortable to the convalescent of the abdomen and on this wire have the hinged a hinged arranged.

What I claim as my invention is the combination of the above described hinged with the ball and so constructed as partially to cover the aperture of the scrotum. In testimony that the above is a true specification of my said improvement as above described I have hereunto set my hand this first day of June in the year of our Lord eighteen hundred and thirty six
